UNITED STATES PATENT OFFICE.

THEODORE G. McGIRR, OF SPRINGFIELD, MASSACHUSETTS.

MACHINE FOR WRAPPING AND SEALING ARTICLES.

1,370,980.

Specification of Letters Patent.

Patented Mar. 8, 1921.

Application filed July 29, 1918, Serial No. 247,180. Renewed August 4, 1920. Serial No. 401,212.

To all whom it may concern:
Be it known that I, THEODORE G. McGIRR, a citizen of the United States, residing at Springfield, county of Hampden, and State 5 of Massachusetts, have invented an Improvement in Machines for Wrapping and Sealing Articles, of which the following description, in connection with the accompanying drawings, is a specification, like characters 10 on the drawings representing like parts.

The invention to be hereinafter described relates to machines for wrapping articles, and more particularly to means for sealing the wrappers for the articles.

15 It is customary to provide a wrapper for an article of paper or fabric impregnated with wax. This is desirable not only because it prevents ingress of moisture to the article and provides a sanitary wrapping, 20 but also because the wax may be readily softened by heat sufficiently to serve as an adhesive for securing the overlapping parts of the wrapper together.

Heretofore, apparatus has been devised 25 for heating and softening wax to cause the overlapping parts of the wrapper to adhere together, but said apparatus has been found to be objectionable for various reasons. Among others, it is bulky, cumbersome and 30 expensive in construction and operation. Also, by said apparatus it is difficult to maintain the proper temperature to soften the wax the degree required without overheating the same. Furthermore, this apparatus 35 acts on the articles while in motion with consequent liability to disturb the overlapped parts of the wrapper and produce an imperfect package.

The present invention provides a simple, 40 compact and economical sealing means for the wrappers, and overcomes the aforesaid objections.

The character of the invention will be best understood by reference to the following description of one good form thereof 45 shown in the accompanying drawing, where- in:—

Figure 1 is a side elevation of a sealing mechanism embodying the invention;

50 Fig. 2 is a plan of the mechanism shown in Fig. 1;

Fig. 3 is a view partly in side elevation and partly in vertical section showing the sealing mechanism and a portion of a wrapping machine to which the sealing mechanism 55 may be applied;

Fig. 4 is a view partly in elevation and partly in section of the electrical device for softening the wax of the overlapped parts 60 of the wrapper;

Fig. 5 is a view of parts shown in Fig. 1 adjusted to a different position; and

Fig. 6 is a perspective view of a wrapped package sealed by the machine.

Referring to the drawings, the sealing 65 mechanism is shown therein applied to a machine for wrapping articles in its general construction and principle of operation similar to the machine shown in Letters Patent of the United States, No. 70 1,091,684, granted to me March 31, 1914. Merely a sufficient portion of said machine is illustrated herein to enable a ready understanding of the application of the sealing 75 mechanism thereto.

This machine includes a rotary carrier 1 (Fig. 3) mounted on a shaft 3 and having a series of pockets 5 for receiving the articles and holding the same while they are wrapped, each of said pockets having a movable spring-pressed side 7. The articles are progressively fed to the carrier and the latter is rotated step by step, and in the course of its rotation, devices act on the wrapper to perform progressively the necessary folding operations. Since these devices do not form part of the present invention, and are sufficiently illustrated in said patent, it is unnecessary to show and describe the same 80 fully herein. It will suffice for the purposes 90 of the present application to refer to means for performing two of the folding or wrapping operations. These means, in the present instance, comprises a tucker 9 (Figs. 1, 2, 3 and 5) provided with arms 11 adapted to tuck in end portions of the wrapper, said tucker being connected to a head 13 which may be reciprocated by suitable means not shown, to cause the tucker to move to its 95 positions shown in Figs. 1 and 5; and rotary 100 folders 14 adapted to fold other end portions after the tucking operation.

The sealing mechanism shown herein as one exemplification of the invention, comprises a support, in the present instance, in 105 the form of a pair of scrolls or plates 15 (Figs. 1, 2 and 3) connected by a bolt 17 having a spacing sleeve 19 thereon engaging the inner faces of said plates. Rising from these plates are a pair of brackets 21 receiving a rock shaft 23 having a block 25 fast thereon which serves to support a heat ap-

plying device, in the present instance, in the form of a pair of arms 27 pivotally mounted on screws 29 secured to said block 25. The arms 27 may be yieldingly urged toward 5 one another by a coil spring 31 having its ends connected to pins 33 on said arms. These arms may be provided with heads 35 (Fig. 4) for engagement with the upper surface of the wrapper and with flanges 37 10 for engagement with the ends of the wrapper. The spring 31 will serve to press said flanges against the ends of the wrapper, and will allow sufficient relative movement of said flanges to accommodate the same to 15 packages of different lengths.

Suitable means may be provided to heat the heads and flanges to enable the same to soften the wax of the wrapper sufficiently to cause the overlapped parts of the wrapper 20 to adhere. To accomplish this, in the present instance, the heads 35 are formed to present sockets for receiving resistance coils 39 connected to conductors 41 projecting through caps 43 at the outer ends of the 25 heads and leading thence to a block 45 above said heads having an insulation sleeve 47 secured in an arm 49 fast on the rock shaft 23, referred to. This arm may have a suitable heat resisting handle 51 at the free 30 end thereof to enable convenient manual rocking of the arm as desired. The conductors 41 may be inclosed in an insulation tube 53 which may project through the block 45 and the sleeve 47 and lead to a suitable 35 source of electricity.

Suitable means may be provided to press the heads 35 against the upper surface of the wrapper. This means, in the present instance, comprises a helical spring 55 having one end connected to a pin 57 on a bracket 59 at one side of one of the plates 15, referred to, the opposite end of said spring being connected to an arm 61 fast on the rock shaft 23. 40 It is desirable that the sealing device carried by the arm 49 should be moved from its active position when the carrier is rotated, in order that the heads 35 and flanges 37 of said device may not engage the 45 wrapper and disturb the same in the course of the rotation of said carrier. To accomplish this, in the present instance, a crank 63 (Figs. 1, 2 and 5) may be provided having one end fast on the rock shaft 23, and 50 its opposite end connected to one end of a link 65 having an elongated slot 67 therein receiving a pin 69 projecting from the tucker head 13, referred to.

The construction is such that when the 60 head 13 moves in a direction to withdraw the tucker from a package, the link 65 and crank 63 will rock the sealing device in a clockwise direction (Fig. 1) and move the same up from its active position shown in 65 Fig. 1. On the other hand, when the tucker

head 13 moves toward the carrier, it will allow the spring 55 to rock the sealing device in a contra-clockwise direction down to its active position shown in Fig. 1. However, the rocking movements of the sealing device always occur at a time when the package carrier is stationary, and thus the device will not wipe against the wrapper and disturb the same during the rotation of the carrier. 75

At times it may be desirable to rock the sealing device from its full line position shown in Figs. 1 and 3 to an inoperative position shown in dotted lines in Fig. 3. This may be accomplished manually by 80 grasping the handle 51 and rocking the arm so that the spring 55 will be carried from its position at the left of the rock shaft 23 past the dead center of said rock shaft to a position at the right thereof. Thus, said 85 spring may serve not only to rock the sealing device and press the heads 35 against the wrapper, but also may serve to hold the device in inoperative position.

After the sealing device has softened the 90 wax and rendered the same sufficiently adhesive to cause the overlapped parts of the wrapper to stick together, it is desirable to cool the wrapper and cause the softened wax to set or harden and permanently secure the 95 overlapped parts together. To accomplish this, a cooling device may be provided, in the present instance, in the form of a plate 71 (Figs. 1, 2 and 3) having ears 73 pivotally mounted on the rock shaft 23, said plate 100 being provided with a series of ribs 75 spaced to provide an extended surface or grid for dissipating the heat. The lower edges of these ribs may be formed to present a rest 77 (Fig. 1) for engagement with 105 the upper surface of the wrapper, and the plate may be supported by lugs 78 on the plate engaging the scrolls 15. This cooling device may rock downward and cause the rest 77 to engage the package, and not 110 only serve to dissipate the heat therefrom, but also serve to press or maintain overlapped parts of the wrapper in engagement with one another.

The operation of the mechanism will be 115 readily understood from the foregoing description thereof. Packages such, for example, as the package 79 (Fig. 6) held in the pockets of the carrier will be successively presented to the sealing device, which 120 will be automatically rocked down to its active position where the spring 55 will press the heads 35 against the overlapped parts of the wrapper at the upper surface 125 81 of the package, and the spring 31 will 125 rock the flanges 37 inward and cause the same to press against the overlapped parts of the ends 83 of the wrapper. The electric current passing through the resistance coils is such that the heads and flanges are heat- 130

ed to the proper temperature for softening the wax the right amount to render the same adhesive. After the overlapped parts of the wrapper of one package have been rendered adhesive by the sealing device, the carrier is rotated to present the sealed wrapper beneath the cooling device, and another package is simultaneously introduced to the sealing device. Thus, the 10 wrappers are successively sealed and cooled in the course of the rotation of the carrier.

While the mechanism has been described more particularly with reference to the softening of a wrapper impregnated with wax, 15 it will be understood that it may be used to soften and render adhesive other suitable fusible substances applied to the wrapper.

By the invention described, simple, compact and efficient unitary means is provided 20 for sealing the wrappers of the articles.

It will be understood that the invention is not limited to the specific embodiment shown, but that various deviations may be made therefrom without departing from the 25 spirit and scope of the appended claims.

What is claimed is:—

1. In a wrapping machine, the combination of side plates, a carrier movable between said side plates having provision for receiving articles having wrappers treated with a fusible substance, said carrier being movable step-by-step to admit successive folding operations on the wrappers, means adjacent said carrier for automatically performing a 35 wrapping operation, a sealing device for the wrappers, a support therefor carried by said side plates, and connections between said sealing device and said means for performing the wrapping operation, for automatically intermittently moving said sealing device toward and from articles on the carrier while the latter is stationary.

2. In a wrapping machine, the combination of a carrier for articles having wrappers treated with a fusible substance, means adjacent said carrier for automatically intermittently performing a wrapping operation while the carrier is stationary, a sealing device for the wrappers, and connections between said sealing device and said means for performing the wrapping operation for automatically moving said device toward and from the articles on the carrier while the latter is stationary.

3. In a wrapping machine, the combination of a carrier for intermittently feeding articles having wrappers treated with a fusible substance, means adjacent said carrier for automatically intermittently performing 55 a wrapping operation, a sealing device for

the wrappers movable toward and from the carrier, spring means for pressing said sealing device against the wrappers while the carrier is stationary, and means coöperating with said means for performing the wrapping operation for automatically moving the sealing device away from the carrier to prevent pressure of said device on the articles during the feeding movement of the carrier. 65

4. In a wrapping machine, the combination of a support, a carrier adjacent said support for feeding articles having wrappers treated with a fusible substance, a shaft mounted on said support, a member mounted on said shaft, a sealing device on said member movable toward and from said carrier, an electric heater for said sealing device for maintaining the same at a predetermined temperature for sealing overlapped parts of the wrapper, and a cooling device mounted 70 on said shaft and adapted to press against the articles to dissipate the heat from the overlapped parts of the wrappers and maintain the same in engagement.

5. In a wrapping machine, the combination of a carrier for articles having wrappers treated with a fusible substance, and means for sealing overlapped parts of the wrapper including a support, a pair of members movably mounted on said support for engagement with one face of the wrapper and having flanges projecting therefrom for engagement with opposed ends of the wrapper, electric heating coils for said members and flanges, spring means for urging said members toward each other to press said flanges against the ends of the wrapper, spring means for pressing said members against the face of the wrapper, and means for moving said members and their flanges bodily 95 away from the article after sealing the wrapper therefor.

6. In a wrapping machine, the combination of a carrier for articles having wrappers treated with a fusible substance, a support, a shaft mounted on said support, an arm on said shaft provided with a handle, a sealing device carried by said arm comprising a pair of members for engagement with a face of the package and having flanges for engagement with opposed ends of the package, spring means for urging said members toward each other to press said flanges against said ends, spring means for pressing said members against said face of the package, and electric heater coils mounted in said members for heating the same.

In testimony whereof I have signed my name to this specification.

THEODORE G. McGIRR
